Inventor,

Emily W.T. Mazars;

By A. Blipham,
Attorney.

UNITED STATES PATENT OFFICE.

EMILY W. T. MAZARS, OF SUFFIELD, CONNECTICUT.

CANNING DEVICE.

1,370,336.

Specification of Letters Patent.

Patented Mar. 1, 1921.

Application filed February 24, 1920. Serial No. 361,052.

To all whom it may concern:

Be it known that I, EMILY W. T. MAZARS, a citizen of the United States, and a resident of Suffield, in the county of Hartford and State of Connecticut, have invented 5 certain new and useful Improvements in Canning Devices, of which the following is a full, clear, and exact specification.

In putting up fruit and other vegetable 10 products in glass jars, it is customary to have a glass top fastened upon the mouth of the jar by means of wire clamping means, a rubber washer being introduced between the top and the edge of the jar-mouth. It 15 is the practice, after filling the jar, to apply the washer and top, partially fasten the top in place by means of part of the wire clamp, and then to stand them in a kettle of water and subject to boiling for several 20 hours until thoroughly sterilized; after which the top is tightly clamped on.

During this sterilizing process, the rubber bands frequently are forced out from between the top and jar until they are almost 25 hanging from the jar and cannot make an air-tight seal. Consequently, the top must be removed, a new rubber band substituted, and the sterilizing done over again.

The object of this invention is the construction of means whereby the rubber band 30 can be largely protected from the injurious effect of the sterilizing heat, and also confined in place until the canning process has been completed. To this end I have provided a metal band made more or less heat- 35 resisting, and adapted to inclose the protruding edge of the rubber band against the action of steam and hot water.

Referring to the drawings forming part 40 of this specification, Figure 1 is an elevation of the upper part of a glass jar and top, showing its rubber washer protected by a device embodying my invention, the same being in section. Fig. 2 is a plan 45 view of one form of the protector. Fig. 3 is a plan view of another form thereof. Fig. 4 is a plan view of still another form of the same. Fig. 5 is a cross section of the protector on an enlarged scale.

50 In the drawings, the reference numeral 1 designates a glass jar of well known form, having a neck 2, and a removable top 3, a rubber washer 4, and wire clamping device 5. The protector 6 consists of a metal 55 annulus, preferably resilient, and made crescent-shaped in cross section.

In the form of the device illustrated in Fig. 2, it is held in place about the rubber washer by its own resiliency, but in the other two forms it is mechanically fastened 60 together, either by means of the well-known buckle 7 shown in Fig. 3, or by means of one or more stove bolts 8, as in Fig. 4.

The edges and outer surface of this annulus are covered by a felt or fabric tape 65 9 confined thereto by being gripped by the bent in edges of the metal, as shown in Fig. 5.

The device is used in the following manner: The jar having been filled, and the 70 washer and top applied thereto, the protector annulus 6 is clasped about the washer, the projecting edges of the latter entering the concavity of the annulus whose fabric-covered edges rest against the top and neck 75 of the jar. One of the two wire sections of the clamping device 5,—the one which serves as the clamping lever,—is then brought up over the top 3, and the jar inserted in the sterilizer kettle. During this 80 action, the fit of the fabric-covered edges 10 against the glass of the jar-neck 2 and top 3 serves to keep the hot water and steam from reaching the rubber washer 4, while the fabric upon the exposed surface of the 85 annulus keeps the heat from striking through and acting upon the washer. Not only does this save the rubber washer from deterioration from the heat, but at the same time it confines the washer in place so that 90 it cannot be forced out from under the top.

The sterilizing having been finished, the jar is removed from the kettle, the other wire of the clamp 5 turned up over the top 3, and the lever portion forced down 95 to clamp the top firmly in place. Then the annulus 6 is pulled out from between the clamping wire and the jar-neck.

If the protector annulus is of the forms shown in Figs. 3 and 4, it is, of course, 100 necessary first to unfasten the buckle 7, or unscrew one or both the stove bolts 8.

Thus protected, the rubber washers will be preserved from injury and displacement, and the work of canning fruit and vegetables rendered far easier and more certain 105 in its results.

What I claim is:

1. A means for protecting the rubber washers in canning, consisting of a substantially annular device made concave internally in cross section, and having its edges 110

provided with a yielding material, for inclosing the protruding edge of the washer and contacting water-tight with the surface of the jar and cap above and below the washer.

2. A means for protecting the rubber washers in canning, comprising a length of resilient sheet metal curved into a substantial annulus, and made concave interiorly

in cross section, the edges thereof being bent 10 over double, and a length of fabric having its edges clamped in place by said bent over edges and inclosing both the latter and one surface of the metal.

In testimony that I claim the foregoing 15 invention, I have hereunto set my hand this 20th day of February, 1920.

Mrs. EMILY W. T. MAZARS.
